UNITED STATES PATENT OFFICE.

GUSTAV B. PETSCHÉ, OF PHILADELPHIA, PENNSYLVANIA, ASSIGNOR TO SOUTHWARK FOUNDRY & MACHINE COMPANY, OF PHILADELPHIA, PENNSYLVANIA, A CORPORATION OF PENNSYLVANIA.

ADMISSION-VALVE FOR GAS-ENGINES.

No. 909,214.

Specification of Letters Patent.

Patented Jan. 12, 1909.

Application filed January 9, 1905. Serial No. 240,152.

To all whom it may concern:

Be it known that I, GUSTAV B. PETSCHÉ, a subject of the Emperor of Germany, residing in the city and county of Philadelphia, in the State of Pennsylvania, have invented a certain new and useful Improvement in Admission-Valves for Gas-Engines, of which the following is a true and exact description, reference being had to the accompanying drawings, which form a part thereof.

My invention relates to gas engines and has for its object to provide an improved admission valve and valve actuating mechanism for use with such engines.

My invention is characterized by the provision of novel means for operating the admission valve mechanism, so that the air and gas mixture is formed of such proportions and so admitted as to give the best results under varying conditions of service.

By means which I prefer to employ, the character of the air and gas mixture may be varied manually at will by varying the area of one of the admission ports and the opening of the air and gas ports into the mixing chamber is controlled by a governor responsive to speed conditions of the engine while the opening of the mixing chamber to the engine cylinder is independent of the governor, but occurs at a point fixed with reference to travel of the engine piston.

My invention has also to do with the general simplification of the valve mechanism, and will be best understood as described in connection with the drawings in which it is illustrated, and in which—

Figure 1, is a side elevation of a gas engine embodying my improvements. Fig. 2, is a side elevation on a larger scale showing the engine cylinder, the valves and valve actuating mechanism. Fig. 3, is a cross-sectional view taken through the cylinder and exhaust valve on the line 3—3, of Fig. 2.

Fig. 4, is a similar sectional view of the cylinder showing the admission valve and its connections in section, and Fig. 5, is a perspective and partly dissected view showing the mechanism by which the governor acts upon the hook detaching device and its actuating mechanism.

A, indicates the bed plate of the engine, A', the housing for the main shaft, A², the main frame casting of the engine; A³, the base on which the cylinder is supported and

A⁴, the base and guideway for the end of the shaft.

B, is the engine cylinder on which is supported, as shown in Figs. 3 and 4, upright standards B², B², etc., one at each end of the cylinder.

B³, B³, are brackets supported on the side of the cylinder, as shown, and B⁴, indicates the piston rod.

C¹, and C², indicate the admission valves. D¹, and D², the exhaust valves.

E, E, are guides supported on the brackets B³, and having parallel guideways E², for the cam supporting blocks to be described. They also support the lugs or bearings E³, E³, which in turn support the lever pivots E⁴.

F¹, and F², are rock levers placed to work with the front pair of reciprocating cams.

G¹, and G², are similar rock levers placed so as to work in connection with the rear pair of reciprocating cams.

H, H, etc., are the cam blocks supporting cams I¹, I², and J¹, J². These cam blocks or slides are connected with the front and rear reciprocating rods H¹, and H², which are in turn connected through the rods H⁴, and H⁵, with the levers H⁶, and H⁷, which, through the connecting rods H⁸, and H⁹, are coupled to the eccentrics H¹⁰, and H¹¹, on a shaft H¹², to which shaft is also attached the bevel gear H¹³, driven through a bevel gear H¹⁴, by a shaft H¹⁵, which in turn is driven through the bevels H¹⁶, and H¹⁷, by the main shaft H¹⁸, of the engine. The eccentrics are placed at 90° apart in order to give the proper motions to the two series of cams. The general arrangement of cams and cam actuating mechanism described when used to actuate the valves of a gas engine is new with me and forms the subject matter of another application for Letters Patent filed December 30, 1904, Serial Number 238,917.

Referring now to the admission valve; K, indicates the admission valve casing provided, as shown, with an air admission port K¹, and a gas admission port K², the gas admission port, by preference, opening upward, as indicated at K³, and this gas port being also preferably regulated in area by the shifting up and down of the sleeve K⁷, which has a screw thread engagement with a vertical wall around which it lies and is turned, and in consequence moved up or

down by the turning of the gear wheel K^8 , the teeth of which engage with teeth on the outer surface of the sleeve and the gear wheel being turned through its spindle K^9 , which, as shown, extends through the bottom of the valve casing K .

K^4 , is a chamber in the valve casing which may be called a mixing chamber and which opens through the valve seated port K^5 , into the engine cylinder.

K^6 , indicates the head or cover of the valve casing and is centrally perforated as shown to give passage to the valve stems to be described.

15 L , is a valve stem, the lower end of which is secured to valve L' , which is, by preference formed and adapted as shown to cover and close the gas port K^3 , and also the annular ports which are surrounded by the 20 gas port and by which the air and gas pass to the mixing chamber K^4 . Passing through the sleeve L , is the valve stem M , to the lower end of which is secured the main valve M' , and to the upper end of which is 25 secured the rock lever N , supported on one of the standards B^2 , and having its other end connected through heads N^1 , and rods N^2 , with one of the rock levers actuated by the reciprocating cams, the connection, as 30 described in my former application, already referred to, being for the admission valves of the same cylinder with, at one end of the cylinder, a rock lever actuated by the front cam, and for the other end of the cylinder 35 of a rock lever actuated by a rear cam. In the construction shown the rock lever N , connected with the valve spindle M , is provided with a third arm N^3 , which through links N^4 , N^4 , connect with the pivots N^6 , N^6 , 40 at one end of the T like rock levers N^5 , N^5 , said levers N^5 , turning freely on the short shafts O' , and carrying at the other ends of their arms the pivot pins N^7 , on which is journaled the hook T , having the arm T' , 45 with the hook T^2 , at its end, and having also the lower arm T^3 , extending below the hook, as is well shown in Figs. 4 and 5.

To the outer end of the sleeved stem L , is pivotally attached the outer arms of a lever 50 O , secured to the shaft O' , and having the upwardly extending arms O^2 , O^2 , the ends of which are connected by the hook engaging bar, indicated at O^3 . The shaft O' , supports between the lever arms O , O , the hook dis- 55 engaging cam, indicated at S^{17} , the cam having an oscillatory motion on the shaft O' , imparted to it through the lever arm S^{16} , and the mechanism I am about to describe.

I impart motion to the hook disengaging 60 cam in the construction illustrated from one of the reciprocating rods H' , or H^2 , as shown, the rod H' , to which is fastened the arm S^{14} , connected through a link S^{13} , with the upper end of a lever S^{12} , secured to a 65 rock shaft S^{11} supported in a bracket ex-

tending out from one of the brackets B^3 , and having attached to it the second lever arm indicated at S^{10} , which through a link S^9 , connects with the arm S^8 , of a lever S^8 , S^7 , pivoted at S^6 , and having its arm S^7 , connected through a link S^{11} , with a lever arm S^{16} , attached to the disengaging cam. The pivot S^6 , is adjustable, being secured on the end of a lever arm S^5 , attached to one end of a rock shaft S^4 , to the other end of which 70 rock shaft is attached the lever S^3 , which through a rod or rods, indicated at S^2 , and a bell crank lever S' , is connected with a governor, indicated at S .

The internal construction of the exhaust 80 valves, indicated at D' , D^2 , is shown in Fig. 3; P , indicating the valve casing formed with a cylindrical opening P' , at top, the bottom of the casing being formed by a detachable sleeve seat indicated at P^4 , the 85 valve seat proper being indicated at P^2 .

Q , indicates the cylindrical body of the water cooled exhaust valve moving in the cylindrical portion P' , and Q^2 , the valve proper adapted to seat itself on the seat P^2 . 90 The exhaust valves are actuated through rods R , extending up and connecting at their tops with rock levers of the two sets of rock levers already described so that the 95 two valves at the opposite ends of the cylinder are actuated by cams of the different sets.

The construction of the exhaust valve shown is new with me and forms the subject matter of my application filed March 100 7, 1906, Serial Number 304,626, while the general scheme of actuating both the admission and exhaust valves through the reciprocating cams, forms, as already stated, the subject matter of my application filed December 30, 1904, Serial Number 238,917.

It will be understood that the two rows of reciprocating cams are so placed and shaped that they will through the appropriate rock levers directly acted on by the 110 cams through the rods N^2 and levers N , open and close the valves M' , at the proper times. It will also be obvious that the valve L' , will also be opened at or nearly at the time when the valve M' , opens by the 115 engagement of the hook T^2 , with a crossbar O' , the valve L' , being lifted as the valve M' , descends and permitting the flow of both air and gas into the mixing chamber K^4 , and through the port K^5 , to the engine 120 cylinder. The closing of the valve L' , can either take place at or about the time of the closing of the valve M' , which would be the case if the hook remained in engagement with the bar O^3 , or it may take place at any 125 time before the closing of the main valve after the hook is disengaged from the bar O^3 , and this disengagement is provided for by the oscillating cam S^{17} , which, when moved in an anti-clockwise direction comes 130

in contact with the arm T^3 , of the hooked lever raising this arm and with it the hook to disengage the bar O^3 . The extent of oscillatory motion given to the cam S^{17} , is 5 constant and effected by the reciprocatory motion of the rod H' , but in addition to this constant motion, the angular position of the cam on the shaft O' , is shifted by the action of the governor which by oscillating the 10 shaft S^4 , moves the pivot carrying lever S^5 , up or down so as to shift the position of the pivot S^6 , which as is obvious from the dia- 15 grammatic figure, Fig. 5, will have the effect of shifting the angular position of the cam on the shaft O' , and consequently of varying the time when this cam will act to disengage the hook lever.

My invention is obviously capable of various modifications and changes, both in the 20 construction of the valve itself and of the mechanism for actuating the hook disengaging device or even for actuating the hook. I do not therefore limit myself to the exact 25 construction shown except where my claims are specifically drawn to embody such limitations.

Having now described my invention, what I claim as new and desire to secure by Letters Patent is,

30 1. In a gas engine having an inlet valve casing with separate ports for the admission of gas and air, a mixing chamber and a port leading from the mixing chamber to the engine cylinder, the combination with 35 said casing of a device for contracting at will the area of one of the admission ports leading to the mixing chamber, a valve for opening and closing the port leading

to the cylinder, a valve for opening and closing both of the ports leading to the 40 mixing chamber, means including a reciprocating disengageable hook for opening said mixing chamber valve, means for reciprocating said hook in fixed relation to the movements of the engine piston, a hook disengaging device, means for actuating said hook disengaging device in normally fixed relation to the movements of the piston, and means actuated by a governor, for varying the path of movement of the disengaging 50 device.

2. In a gas engine having an inlet valve casing provided with a mixing chamber and separate air and gas ports leading to said mixing chamber, one wall of the gas port 55 being cylindrical, and a port leading from the mixing chamber to the engine cylinder, a collar adjustable along the cylindrical wall of the gas port for varying at will the area of the gas port, means without the 60 casing for adjusting the collar, a valve for opening and closing communication between the air and gas ports and the mixing chamber, a valve for opening and closing the port leading from the mixing chamber to the engine cylinder, a governor, means for opening and closing said valves, said means including connections from the governor for varying the operation of the valve controlling communication between the air 70 and gas ports and the mixing chamber.

GUSTAV B. PETSCHE.
